(57) **CLAIM**

I claim the ornamental design for a refuse container with lid, as shown and described.

DESCRIPTION

FIG. 1 is a top, front perspective view of a refuse container with lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front perspective view of the refuse container separated from the lid for ease of viewing the design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a top, front perspective view of the lid separated from the container for ease of viewing the design, shown in an open position;

FIG. 16 is a top, front perspective view thereof, shown in a closed position;

FIG. 17 is a front view thereof;

FIG. 18 is a rear view thereof;

FIG. 19 is a left side view thereof;

FIG. 20 is a right side view thereof;

FIG. 21 is a top view thereof; and,

FIG. 22 is a bottom view thereof.

The dash-dot broken lines immediately adjacent to the shaded areas represent bounds of the claimed design and form no part of the claimed design. The dash-dash broken lines show portions of the refuse container with lid which form no part of the claimed design.
